United States Patent Office

Des. 206,065
Patented Oct. 25, 1966

206,065

DENTAL CHAIR

Charles E. Vaughn and Arthur Gilbert Billin, both of Rochester, N.Y., assignors to Ritter Corporation, Rochester, N.Y., a corporation of Delaware

Filed July 6, 1965, Ser. No. 86,059

Term of patent 14 years

(Cl. D15—3)

FIG. 1

FIG. 2

FIG. 3

FIG. 4

FIG. 1 is a top plan view of a dental chair, showing our new design;

FIG. 2 is a side elevation thereof;

FIG. 3 is a front elevation thereof;

FIG. 4 is a rear elevation thereof.

The side of the chair not shown is substantially a mirror image of the side shown.

We claim:

The ornamental design for a dental chair, as shown and described.
